(57) **CLAIM**

The ornamental design for a controller for valves, as shown and described.

DESCRIPTION

FIG. 1 is a top front perspective view of a controller for valves showing my new design;
FIG. 2 is a front view thereof;
FIG. 3 is a rear view thereof;
FIG. 4 is a right side view thereof;
FIG. 5 is a left side view thereof;
FIG. 6 is a top view thereof; and,
FIG. 7 is a bottom view thereof.

The broken lines are included for illustrating portions of the controller for valves and form no part of the claimed design.
